UNITED STATES PATENT OFFICE.

EDUARD SCHMIDT, OF ZIMMERSRODE, PRUSSIA, ASSIGNOR TO LUDWIG SCHÜLKE, OF DUSSELDORF, GERMANY.

RAILWAY-SLEEPER.

SPECIFICATION forming part of Letters Patent No. 349,524, dated September 21, 1886.

Application filed April 22, 1886. Serial No. 199,797. (No model.) Patented in Germany July 14, 1885, No. 34,657.

To all whom it may concern:

Be it known that I, EDUARD SCHMIDT, a subject of the King of Prussia, and residing at Zimmersrode, Kingdom of Prussia, German Empire, have invented new and useful Improvements in Railway-Sleepers, (for which I have obtained Letters Patent in Germany on the 14th day of July, 1885, No. 34,657,) whereof the following is a specification.

1c My invention consists in a new mode of constructing sleepers for railways of worn-out or other rails, of the broad-footed or Vignoles form, such as are generally employed at present for railways.

15 In the annexed sheet of drawings, a sleeper carried out according to my invention is shown in combination with a pair of line-rails, by Figure 1 in sectional elevation, by Fig. 2 in transverse section, and by Fig. 3 in plan. Fig.

2c 4 is a sectional view showing to a larger scale the means for fastening the rails to the sleepers. Figs. 5 and 6 represent in sectional elevation and in transverse section the connection of the rails to each other which I prefer to employ with my sleeper.

25 The sleepers are made out of two pieces of rails, *a*, of suitable length, laid on the side, with their heads in juxtaposition, so that the flanges which form the basis of the rails constitute the ribs that are to project into the ground, while the webs and one side of each of the heads constitute a broad bearing-surface, which rests upon the surface of the ground. The said pieces are connected together mainly 35 by means of plates *b*, forming the bed-plates for the rails of the line *c*. In order to obtain a flat bearing-surface for the plates *b*, suitable recesses are cut into the upper portions of the heads and the flanges of the sleeper-rails 40 down to the webs of the same. On the plates *b* the line-rails *c* are fastened by means of clamping-pieces *d* and by screw-bolts *e*, passing through the said pieces *d*, the bed-plates, and the sleeper-rails. A secure connection of the line-rails with the sleeper-rails and of the latter with each other is thus attained at the same time.

45 For the purpose of preventing the rails *c* from shifting sideward on the sleepers, the recesses of the rails *a* are preferably made of

such width that the plates *b* exactly fit into them. The plates are provided at their sides with ribs, serving as abutments for the clamping-pieces *d*, and these pieces are so adjusted as to fit with their lower portion between the 55 said ribs and the foot of the rail *c*. By making one clamping-plate narrower and the opposite one wider by the same amount the increase in the width of gage required for curves may be produced. (See Fig. 4.) The upper 60 surface of the bed-plates may be made sloping, so as to impart to the rails the necessary inclination toward each other.

The rails carried by the described sleepers may be connected together at their ends in 65 any suitable manner; but I prefer to employ suspended joints, and to secure the rails to each other by fish-plates *f*, Figs. 5 and 6, suitably bent so as to reach over the foot of the rail, and arranged to bear with their ends (which 70 have to be notched for this purpose) upon the adjacent sleepers or the corresponding bed-plates, and to abut lengthwise with their lower portion against the sleepers, so that a longitudinal displacement of the rails may be 75 prevented.

I claim as my invention—

1. A sleeper for railways, consisting of two flanged rails placed with their heads in juxtaposition and secured together, substantially as 80 set forth.

2. A sleeper for railways, consisting of two flanged rails placed in juxtaposition with their webs horizontal, and cross-plates and bolts by which they are secured together, substantially 85 as set forth.

3. A sleeper consisting of two flanged rails placed in juxtaposition with their webs horizontal, the flanges being cut away at suitable distances apart to admit the bases of the track- 90 rails, substantially as set forth.

4. A sleeper for railways, consisting of two flanged rails placed with their heads in juxtaposition and having their flanges cut away at suitable distances apart, in combination with 95 plates fitting in said cut-away places and bolts securing the whole together, substantially as set forth.

5. The combination, with the rails *a a*, placed with their heads in juxtaposition and having 100

their flanges cut away, of the plates *b*, placed in said cut-away places, the track-rails *c*, resting upon said plates, the clamping-pieces *d*, and the bolts *e*, substantially as and for the 5 purposes set forth.

6. A sleeper for railways, consisting of two flanged rails placed in juxtaposition with their webs horizontal and secured together, substantially as set forth.

In testimony whereof I have hereunto set my hand in the presence of two subscribing witnesses.

EDUARD SCHMIDT.
